INSIGNIA PLACING DEVICE FOR
COMBAT JACKETS

Millard F. Thacker, Fort Sam Houston, Tex.

Application November 2, 1950, Serial No. 193,622

4 Claims. (Cl. 33—180)

1

This invention relates to a device for positioning insignia on military clothing.

The object of the invention is to provide a device which will facilitate the accurate attachment of various insignia to the clothing of military personnel.

Another object of the invention is to provide a device which will facilitate the accurate placement of insignia on battle jackets or other uniforms whereby such insignia can be placed properly so as to conform with the appropriate military regulations.

A further object of the invention is to provide an insignia-positioning device which is extremely simple and inexpensive to manufacture.

Other objects and advantages will be apparent during the course of the following description.

In the accompanying drawings forming a part of this application, and in which like numerals have been used to designate like parts throughout the same:

Figure 1 is a front elevational view showing the device of the present invention being used for affixing insignia to military clothing;

Figure 2 is a perspective view of the insignia-positioning device of the present invention;

Figure 3 is a perspective view showing the opposite side of the device.

Referring in detail to the drawings, the numeral 10 designates the insignia-positioning device of the present invention, and the device may be made of any suitable material, such as plastic, wood, metal or cardboard. The insignia-positioning device 10 includes a front wall 11 and the insignia-positioning device may be fabricated of a single piece of material.

Arranged rearwardly or spaced behind the front wall 11 is a back wall 12, Figures 2 and 3, the front wall 11 being wider than the back wall 12. Connecting the back wall 12 to the front wall 11 is a web 14.

The front wall 11 is provided with a pair of spaced, semicircular cutouts or recesses 15 and 16, and these cutouts 15 and 16 are adapted to snugly receive therein insignia, such as the insignia button 18, which is to be affixed to the uniform. Arranged intermediate the pair of cutouts 15 and 16 is a V-shaped notch 17 which is adapted to be arranged in alignment with the notch 19 between the lapel 20 and the collar 21 of the battle jacket or other article of clothing, so as to indicate to the user when the insignia-positioning device 10 is in its proper position.

The front wall 11 has arranged on its outer

2

face the words "Left" and "Right," and these words may be printed or otherwise affixed to the front wall 11.

From the foregoing, it is apparent that a device 5 has been provided which will facilitate or enable persons to properly and accurately affix prescribed insignia of service personnel to their clothing as required by army or other military regulations. In using the device, the front wall 10 11 is arranged adjacent the outer surface of the lapel 20 or collar 21, while the back wall 12 is arranged in slidable engagement with the rear portions of the collar and lapel. Then, the device 15 of the present invention is slid up or down until the notch 17 coincides with the notch 19 between the collar and the lapel, as shown in Figure 1.

Then, the insignia buttons, such as the buttons 18, are arranged in the semi-circular cutouts 20 15 and 16, so that the edges of the insignia buttons 18 are aligned with the edges of the cutouts 15 and 16. Next, the points or prongs of 25 these conventional insignia buttons 18 are projected through the material of the jacket, and the clutch pins are affixed to the prongs. Now, the device 10 of the present invention can be withdrawn so that it can be used over and over again. In solid lines in Figure 1, the device is shown 30 being used for properly affixing or positioning the insignia on the left side of the jacket, but it is to be understood that the device can also be used for positioning the insignia on the right side of the jacket. The words "Left" and "Right" 35 on the front wall 11 indicate to the user which end of the device should be up.

If desired, the shape of the device can be 40 varied, and also only one of the cutouts may be provided if desired. The device of the present invention is especially suitable for placing or properly affixing insignia to combat jackets of military personnel.

I claim:

1. As a new article of manufacture, an insignia-positioning device adapted to be positioned on 45 the lapel of a uniform jacket comprising a front wall, a back wall, a web connecting said front wall to said back wall, there being a pair of spaced semicircular cutouts arranged in the forward edge of said front wall and equally spaced from the ends of said front wall.

2. As a new article of manufacture, an insignia-positioning device adapted to be positioned on the lapel of a uniform jacket comprising a front wall, a back wall, a web connecting 50 said front wall to said back wall, there being a

pair of spaced semicircular cutouts arranged in the forward edge of said front wall and equally spaced from the ends of said front wall, said device being fabricated of a single piece of material.

3. As a new article of manufacture, an insignia-positioning device adapted to be positioned on the lapel of a uniform jacket comprising a front wall, a back wall, a web connecting said front wall to said back wall, there being a pair of spaced semicircular cutouts arranged in the forward edge of said front wall and equally spaced from the ends of said front wall, said device being fabricated of a single piece of material, there being an alignment notch arranged in the forward edge of said front wall between said cutouts.

4. As a new article of manufacture, a device for facilitating accurate attachment of insignia to the lapel of a uniform jacket, said device being fabricated of a single piece of material and comprising a front wall and a back wall, a web connecting said front wall to said back wall, there being a pair of spaced semicircular cutouts ar-

ranged in the forward edge of said front wall and equally spaced from the ends of said front wall, there being a notch arranged in the forward edge of said front wall intermediate said cutouts.

MILLARD F. THACKER.
